US0D1104970S

(12) **United States Design Patent** (10) Patent No.: **US D1,104,970 S**
(45) Date of Patent: ** Dec. 9, 2025

(54) **CHARGING CASE FOR WIRELESS
EARPHONES**

Xiaomi-Redmi-Buds-Wireless-Earphone/dp/B0CQKD5N9X/?th=1
(Year: 2024).*

(71) Applicant: **BEIJING XIAOMI MOBILE
SOFTWARE CO., LTD.**, Beijing (CN)

Primary Examiner — Jae Liang
Assistant Examiner — Caleb M Baker

(72) Inventor: **Yuhao Zhang**, Beijing (CN)

(74) Attorney, Agent, or Firm — Cozen O'Connor

(73) Assignee: **BEIJING XIAOMI MOBILE
SOFTWARE CO., LTD.**, Beijing (CN)

(57) **CLAIM**

(**) Term: **15 Years**

The ornamental design for a charging case for wireless earphones as shown and described.

(21) Appl. No.: **35/522,390**

DESCRIPTION

(22) Filed: **Sep. 14, 2023**

1. Charging case for wireless earphones
2. Charging case for wireless earphones
